(57) **CLAIM**

The ornamental design for a windowed and zippered cover for a water-dispensing bottle, as shown and described.

DESCRIPTION

FIG. 1 is a perspective front and top view of a windowed and zippered cover for a water-dispensing bottle showing my new design, and shown in operative association with a water dispensing apparatus shown in broken line outline and forming no part of this invention;

FIG. 2 is a front view of FIG. 1;

FIG. 3 is a rear view thereof, and,

FIG. 4 is a top plan view thereof.

The broken lines in FIGS. 1 and 2 are for illustrative purposes only and form on part of the claimed design.
